UNITED STATES PATENT OFFICE.

SWITS CONDÉ, OF OSWEGO, NEW YORK.

CIRCULAR-KNITTING MACHINE.

SPECIFICATION forming part of Letters Patent No. 245,137, dated August 2, 1881.

Application filed May 17, 1881. (No model.)

To all whom it may concern:

Be it known that I, SWITS CONDÉ, of Oswego, in the county of Oswego, in the State of New York, have invented new and useful 5 Improvements in Circular-Knitting Machines, of which the following, taken in connection with the accompanying drawings, is a full, clear, and exact description.

This invention relates to certain mechanism 10 designed to be applied to a rotary knitting-machine, and by means of which said machine is adapted to knit fabric striped as well as blocked or checkered in different colors.

In the annexed drawings, Figure 1 is a side 15 view of my invention; Fig. 2, a plan view of same; Fig. 3, a front view; and Figs. 4 and 5 are enlarged detail views, illustrating the effect of certain parts of the mechanism employed in my invention.

20 Similar letters of reference indicate corresponding parts.

A represents the usual rotary needle-cylinder, carrying vertically at its periphery the bearded needles N.

25 L is the loop-wheel, sometimes called "burr," arranged on the outside of the needle-cylinder to force into the beards of the needles the thread or yarn to be knitted. Said thread is guided to the burr L by a bar, a, which is 30 fixed to the side of the standard s and has its forward extremity in proximity to said burr, and provided with an eye, through which the thread passes on its way to the burr. In this invention, however, two or more threads of 35 different colors are conducted to the eye of the stationary thread-guide a by means of two vibratory thread-guides, b b', pivoted to the side of the thread-guide a. The thread-guides b b' receive vibratory motion by two pitmen, d d', 40 connected to them, respectively, and to a rock-arm, c, pivoted on a standard, n, secured to the table of the machine in front of the needle-cylinder.

To the side of the standard n is pivoted a 45 lever, e, the forward end of which is extended under the needle-cylinder A, and the rear end is connected with a rearward extension, i, of one of the vibratory thread-guides by a pitman, d'.

50 By means of cams f f, placed at intervals on the under side of the needle-cylinder, the for-

ward end of the lever e is intermittently depressed when the cylinder is in motion. The resultant alternate depression and elevation of the rear end of said lever imparts a vibratory motion to the thread-guide, with which it is connected by the pitman d', and said vibratory motion is transmitted to the other thread-guide, b, by the connection of the two pitmen d d and rock-arm c, which latter causes one of 60 said thread-guides to rise while the other descends. The period during which the thread-guides b b' are held in their respective elevated positions depends on the length of and distance between the cams f f on the needle-cylinder. The elevation of one thread-guide throws its thread above that of the other thread-guide and simultaneously increases the tension of the elevated thread. The two threads are in that condition carried into the beards 70 of the needles N by the burr L.

The previously-formed loop of the fabric, which, during the last-described operation, has been held below the beard of the needle by the usual and well-known depressor R, is then 75 drawn up over the outside of the beard of the needle and off the end of the same to form a new loop with the threads in the beard of the needle. In this operation said previous loop draws the lower and slack thread back of the 80 upper and taut thread, thus presenting different colors at opposite sides of the fabric. The alternation in the movement of the vibratory thread-guides b b' at certain intervals during 85 each revolution of the needle-cylinder produces vertical stripes in the fabric. Since the elevation of one of the vibratory thread-guides causes the respective thread thereof to predominate at one side of the fabric, it is evident that by maintaining said thread-guide in its 90 elevated position during a number of revolutions of the needle-cylinder a horizontal stripe is produced in the fabric. Therefore by checking the alternation in the elevation of the two thread-guides b b' after a certain number of 95 rotations of the needle-cylinder, and maintaining one of them in its elevated position for the next number of revolutions of said cylinder, as before described, the vertical stripes are broken and converted into rectangular blocks 100 or checkers by the interspersion of horizontal stripes. To automatically produce this effect

I employ, in conjunction with the before-described devices, the following instrumentalities, viz: Near the rear end of the lever *e*, I arrange a ratchet-wheel, *W*, mounted horizontally on a post, *m*, secured to the table of the machine. The upper surface of said ratchet-wheel is provided with a cam, *g*, in the form of a semicircular raised rim extending half-way around the ratchet-wheel. From the rear end of the lever *e* projects an arm, *h*, having a friction-roller by which it rests on top of the ratchet-wheel *W*.

On the post *m* is pivoted a lever, *u*, which is extended to the needle-cylinder *A*, and has its extremity in the path of a cam or projection, *k*, on the exterior of the needle-cylinder. Said lever *u* is held in opposition to the approach of the cam *k* by a suitable spring, *l*, pressing said lever in an opposite direction to that of the rotation of the needle-cylinder. A stop, *o*, attached to the post *m*, arrests the last-described spring action of the lever *u* at a point to cause it to be encountered by the cam *k*. To the lever *u* is connected a pawl, *p*, which engages the ratchet-wheel *W* at each swinging of said lever by the cam on the needle-cylinder, thus causing the ratchet-wheel to turn a certain distance at each revolution of the needle-cylinder. This ultimately brings the cam or raised portion *g* of the ratchet-wheel under the arm *h* of the lever *e*, and raises the rear end of said lever, so as to depress the forward end thereof sufficiently to clear the cams *f* under the needle-cylinder. The lever *e* is held in this position until its arm *h* leaves the cam *g*, thereby holding the vibratory thread-

guides *b b'* dormant during a certain number of revolutions of the needle-cylinder, and by the resultant unvaried feed of the threads or 40 yarns producing a horizontal stripe across the fabric. As soon as the ratchet-wheel *W* is actuated often enough to carry its cam *g* from under the arm *h* the lever *e* drops back into the path of the cams *f* and resumes its intermittent oscillating motion, and thus produces the vertical stripes until the next encounter of the cam *g* with the arm *h*, when the vertical stripes are again broken by the interspersion of horizontal stripes, and thus caused to present a blocked or checkered configuration. 45

Having described my invention, what I claim is—

The loop-wheel *L*, the two pivoted thread-guides *b b'*, one of which has the rearward extension, *i*, the pitmen *d d*, rock-arm *e*, pitman *d'*, pivoted lever *c*, said lever having one end extended under the needle-cylinder and provided at the opposite end with the arm *h*, the ratchet-wheel *W*, provided with the cam *g*, the 55 spring-restrained lever *u*, provided with the pawl *p*, and the needle-cylinder *A*, provided with cams *f* and *k*, all combined and arranged substantially as described and shown.

In testimony whereof I have hereunto signed my name and affixed my seal, in the presence of two attesting witnesses, at Oswego, in the county of Oswego, in the State of New York, this 30th day of April, 1881. 60

SWITS CONDÉ. [L. S.]
